UNITED STATES PATENT OFFICE.

JOHN PLETTNER, OF AI, OHIO.

WASHING-MACHINE.

SPECIFICATION forming part of Letters Patent No. 392,880, dated November 13, 1888.

Application filed October 27, 1887. Serial No. 253,541. (No model.)

To all whom it may concern:

Be it known that I, JOHN PLETTNER, a citizen of the United States of America, residing at Ai, in the county of Fulton and State of Ohio, 5 have invented certain new and useful Improvements in Washing-Machines; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention relates to certain new and useful improvements in washing-machines; and it consists in the construction and arrangement of the parts thereof, which will be more fully hereinafter described, and pointed out in the claim.

20 The essential feature of my invention is the provision and use of sliding washer-frames acting conjunctively with and against a centrally-situated oscillating rubber, which is, in connection with a rock-shaft, operated by a depending swinging lever.

25 The object of my invention is to facilitate the washing of clothes by the sliding washers drawing the same against the oscillating rubber, and thereby acting similarly to the ordinary form of wash-board.

30 A further object of my invention is to provide positively-acting mechanism in connection with the machine for removing the same from one position to another.

35 I attain these objects by the construction illustrated in the accompanying drawings, wherein like letters of reference indicate similar parts in the several views, and in which—

Figure 1 is a perspective view of my improved form of washing-machine. Fig. 2 is a 40 longitudinal vertical section thereof. Fig. 3 is a detail elevation of the depending swinging weighted operating-lever.

A indicates a rectangular washing box having top lids, A², inclined deflectors A' at the inner upper end portions thereof, hand-grips a, and a drain-cock, a', at one end thereof. The box A is secured between inclined legs B B, which extend above the top of the box and are 45 united to form bearings for a rock-shaft, C, which is mounted therein. Suitable metallic

straps, b, are secured over the upper united ends of the legs B, and half-boxes are secured to the inner sides thereof, in which the rock-shaft C has bearing. The one end of the said 55 shaft C projects outward from the side of one pair of legs, and has a depending lever, D, secured thereon, which has a weight, d, mounted on its lower end and a handle or cross-bar, D', secured to the upper portion thereof and 60 held in position in connection therewith by means of a metallic strap, d'.

The shaft Chas an arm, C', formed therewith at an angle thereto, and is pivoted at its free end to the upper end of a pitman-bar, C², by 65 means of metallic straps c. The said pitman-bar passes through a slot in the lids of the washing-box, and is secured at its lower end to one side of a semi-cylindrical rubber, E, by metallic straps c'. The rubber E is formed 70 with a series of slats, e², arranged closely together and having apertures e' therein to permit the water to pass therethrough. The slats e² are held and supported in position by two circular end frames, E', which are formed with 75 stub-shafts engaging with journal-boxes e, secured to the inner sides of the box A. Suitable cross-braces, e³ and e⁴, are secured to the end frames, E', the braces e⁴ being of angular formation and adapted to prevent displacement of the slats e².

To the upper portion of the end frames, E', arms E² are pivotally secured, the said arms being integrally formed with the upper portion of sector-frames F, which embrace a series of 85 slats, f, having apertures f² therein for the passage of water therethrough. With the lower rear portion of each frame F eyes f' are integrally formed, through which the angularly-bent portion of tie-rods F' pass, the upper portion of said tie-rods being secured in the sides of the washing-box and limit the movement of the frames F.

To the under side of the box A a journal-box, g, is secured, through which the bent portion of a lever-arm, G', passes, and which projects from said box g along the side of the box, and is adapted to engage with a cleat, b', secured to the side thereof. From the journal-box g the said lever G' extends downward and 90 is secured to a stub-shaft upon which a wheel, G, is mounted. By raising the lever G' and

placing the same between the parts of the cleat *b* the box *A* is raised, and by grasping the hand-grips *a* the machine can be readily moved from one position to another.

- 5 The clothes to be washed are placed between the frames *F* and the centrally-situated rubber *E*. By swinging the lever *D* from one side to the other the rock-shaft *C* is set in motion, which in turn oscillates the rubber *E* through 10 the medium of the pitman-bar *C'*. As the rubber *E* is oscillated the one frame *F* is drawn toward the rubber and the other forced away therefrom. The clothes are alternately drawn 15 toward and fall away from the rubber *E* by this movement, and as they are brought up to the rubber the parts are so timed that they will be held thereagainst until the said rubber passes partially over the surface thereof. When the clothes are drawn toward the rubber *E*, the water is partially wrung out of the 20 same, and when released therefrom fall into the water and are rinsed until they are again gathered and brought toward the rubber *E* by the sliding washers *F*.
- 25 The clothes are quickly and thoroughly washed by my improved form of washer and the dirt eradicated therefrom by an alternate rubbing and rinsing process, as above described.
- 30 The utility, convenience, and adaptability of my improved machine being obviously apparent, it is unnecessary to further enlarge upon the same herein.

Having thus described my invention, what I claim as new, and desire to secure by Letters 35 Patent, is—

In a washing-machine, the combination of the washing-box having the end deflectors, *A'*, the rock-shaft mounted above said box in the upper united ends of the angularly-arranged 40 legs and having the central integral short arm, *C*, the said legs being mounted in pairs on each side of the box; as set forth, the centrally-situated oscillating rubber having end circular frames journaled in the inner sides of the box, 45 the pitman-bar connected to the central arm, *C'*, of the rock-shaft *C* at its upper end and to the center of one edge of the oscillating rubber at its lower end, the curved semi-rotary washer-frames mounted on each side of the 50 central rubber and pivotally secured to the end circular frames thereof, the tie-rods *F'*, connected to the washer-frames and to the inner sides of the box to limit the movement of said frames, and the depending swinging weighted 55 lever for operating the parts, substantially as described.

In testimony whereof I affix my signature in presence of two witnesses.

JOHN PLETTNER.
